H. S. JARNAGIN

LOCOMOTIVE BOILER CONSTRUCTION

Filed Nov. 26, 1924

Inventor:
Harry S. Jarnagin.
By *Fred J. Hanson*
Attorney.

UNITED STATES PATENT OFFICE.

HARRY S. JARNAGIN, OF RICHMOND HEIGHTS, MISSOURI, ASSIGNOR OF ONE-HALF TO
ROBERT W. BIDWELL, OF RICHMOND HEIGHTS, MISSOURI.

LOCOMOTIVE-BOILER CONSTRUCTION.

Application filed November 26, 1924. Serial No. 752,442.

My invention relates to locomotive boilers, and it is a distinct and practical improvement to overcome certain practical objections to, and defects in, boiler construction 5 of the present types for locomotives.

The objects of my present invention are to provide a boiler structure with baffle means at opposite ends of the boiler tubes to prevent the live gases, heat and smoke 10 from passing directly through all the tubes in one direction only, but diverting the same to travel back again at a higher elevation and then finally forward to the stack, thereby lowering the stack temperature to a minimum 15 and distributing the heat along its path of travel where it is most useful.

A further object of the invention is to provide rear and front baffles, so arranged with relation to the tubes as to have a larger 20 number of tubes for the smoke and live gases to first pass forwardly through, then a less number of tubes to carry the same rearwardly at a higher elevation and finally a less number of tubes to carry the gas and 25 smoke forwardly at a still higher elevation for final escape through the smoke stack, this arrangement of means being provided for the reason that the gases shrink in volume as they pass through the tubes in leaving 30 the combustion chamber of the fire box.

A still further object of the invention is to provide a jet blower in advance of the tubes through which the gases and smoke finally pass to the stack so as to eliminate 35 slow fires.

With the above and other objects in view, as will be apparent hereinafter, the invention consists in the novel features of construction, arrangement and combination of 40 parts hereinafter more fully described and finally pointed out in the claims hereto appended.

Referring to the accompanying drawing forming a part of this specification,

The figure is a sectional elevation of a 45 locomotive boiler structure and embodying the features of my invention.

Referring to the drawing, the reference 50 character A represents a locomotive boiler which is provided intermediate its ends with the boiler tubes 1 to provide the fire box combustion chamber 2 and the front boiler chamber 3. The numeral 4 represents a water chamber partly surrounding the fire

box combustion chamber 2 and which communicates with the water spaces 5 above and between the boiler tubes 1.

Disposed within the fire box combustion chamber 2, at the upper front corners thereof, is a hollow baffle wall B consisting of 55 two suitable baffle plates 6, spaced apart to provide a water space 7. The baffle plates 6 are suitably connected at their upper ends to the crown sheet 8 and at their lower ends to the rear end plate, or head 9 of the boiler 60 tubes. The hollow baffle wall B is preferably angular in shape in side elevation, as shown in the drawing, and it provides the rear smoke passage 10 between the rear head 65 9 of the boiler tubes and the fire box combustion chamber 2, and a passage 11 between the lower section of the baffle wall 6 and the lower side of the boiler. The lower end 70 of the baffle wall 6 is connected with the boiler tube end wall 9 so that there are a less number of tubes between the lower end 75 of the baffle wall and the bottom of the boiler than above the lower edge of the baffle wall and the upper side of the boiler, as shown.

Disposed within the front boiler chamber 3 is a suitable baffle plate, or wall 12 which is disposed at an inclined position. The upper edge of the baffle plate, or wall 12 is suitably connected to the front head 13 of 85 the boiler tubes 1 and its lower edge is suitably connected to the lower side of the boiler A, as shown, so as to provide the front smoke passage 14. This arrangement of rear and 90 front baffle walls provides three smoke and live gas tube passes, or passages, designated 15, 16 and 17. The area of the lower tube passage 15 is greater than the middle tube passage 16 and the upper tube passage 17 is smaller in area than the middle tube passage 95 16 so as to compensate for the shrinkage of gases in their path of travel from the combustion chamber 2 to the front boiler chamber 3, from where they escape to the atmosphere through the usual smoke stack 18. It 100 is thus seen that the baffle walls provide an S-shaped path through the boiler tubes for the smoke and gases to follow in passing from the fire box combustion chamber to the smoke stack. The smoke, live gases and heat 105 first pass forwardly through the tubes involved in passage 15, then they are directed rearwardly by the front baffle wall 11 so as

80

105

to pass through the tubes involved in the pass 16 and then the gases are turned again by the rear baffle wall B and directed to move forwardly through the tubes involved 5 in the smallest and upper pass 17 from where they escape through the smoke stack 18.

The reference numeral 19 represents a steam pipe which is directed from the 13 steam dome 20 to a point in advance of the upper gas pass 17 and it is provided with a suitable jet to spray a stream of steam forwardly to create a suction toward the smoke stack 18 to eliminate slow fires.

15 From the foregoing description, it is evident that I provide a boiler construction which is highly efficient for the purpose designed.

19 The many advantages of the herein described invention will readily suggest themselves to those skilled in the art to which it appertains.

I do not wish to be understood as having limited myself to the exact details of construction shown and described, but desire to have it understood that the invention I have shown in the drawings is merely illustrative, as it is manifest that various minor changes may be made in the exact construction and 25 particular arrangement of parts without departing from the spirit of my invention, hence I reserve the right to make any such changes or modifications as may fairly fall 30

within the scope of the appended claims when fairly construed. 35

What I claim is:

1. In a locomotive boiler construction, a fire box bounded by a water chamber, boiler tubes in advance thereof and a front compartment for the boiler, a pair of angular 40 spaced baffle plates fixed at their forward ends to the rear tube sheet and at their upper ends to the crown sheet of the fire box to provide a heat and smoke turning compartment in the upper front corner of 45 the fire box to the rear of a predetermined number of upper boiler tubes and to provide a water passage between the plates and an inclined baffle plate in the front compartment fixed at its upper end to the front 50 boiler sheet and at its lower end to the wall of the boiler.

2. A baffle wall for locomotive fire boxes consisting of a pair of spaced angular plates fixed at their upper ends to the crown sheet 55 of the fire box and at their lower ends to the rear boiler sheet to provide a water passage between the plates and a heat and smoke turning chamber to the rear of a pre- 60 determined number of upper tubes of the boiler, said baffle wall being arranged to occupy the upper front corner of the fire box.

In testimony whereof, I have hereunto signed my name to the specification.

HARRY S. JARNAGIN.
